SIDE PLATE FOR FREIGHT CARS

Charles David Bonsall, Pittsburgh, Pa., assignor to
P. H. Murphy Company, New Kensington, Pa.,
a corporation of Pennsylvania

Original application September 17, 1930, Serial
No. 482,422. Patent No. 1,853,655. Divided and
this application January 29, 1932, Serial No.
589,607

6 Claims. (Cl. 108—5.7)

The subject matter hereof is divided out of my application Serial No. 482,422, filed September 17, 1930, for patent for Metal car roof, now Patent No. 1,853,655.

5 The present invention relates to metal side plates for freight cars, especially box cars of the kind provided with metal carlines and roof sheets supported on said side plates. The principal object of the present invention is to devise a strong and durable side plate construction that will better provide for the supporting, positioning and securing of the carlines. The invention consists principally in providing the side plates with portions or members that serve as supports for the end portions of the roof sheets and have pockets located and arranged to receive the ends of the carlines which are riveted thereto. It also consists in the arrangements and combinations of parts hereinafter described and claimed.

In the accompanying drawing, which forms part of this specification and wherein like symbols refer to like parts wherever they occur,

25 Fig. 1 is a plan view of a portion of the car equipped with side plate constructions embodying my invention.

Fig. 2 is a vertical transverse section through the car at the eaves of the roof,

30 Fig. 3 is a vertical cross-section on the line 3—3 of Fig. 2.

Fig. 4 is a side view of a portion of a side plate construction; and

Fig. 5 is a vertical cross-sectional view of a modified form of side plate with the roof sheet and carline support made integral therewith.

The present construction comprises side plates 1 of Z-section with the inner leg 2 upstanding and having riveted flatwise against the outer side of said leg an angle shaped member 3 whose upper leg 4 extends inwardly over the top of the side plate at an angle conforming to the pitch of the roof and at the proper elevation for the end portions of the roof sheets 5 to rest upon.

5 At suitable intervals, such angle support 3 has depressions 6 in its top of proper shape to receive and form seats for the ends of the carlines 7, which are riveted thereto. Such seats are deep enough to bring the tops of the eaves portions of the carlines to the height desired.

The carlines are made of two members each. The upper member 8 is in the form of an inverted channel with outturned horizontal flanges at the bottoms of their sides; and the lower carline member 9 is in the form of a plate that extends the full length of the carline and is riv-

eted to the bottom flanges of said inverted channel member. This bottom member is wider than the upper member of the carline and has its marginal portions struck up beyond the margins of the inverted channel shaped member into the form of raised horizontal flanges 10 that are of proper height for the side marginal portions of the roof sheets to rest upon.

The side marginal portions of the roof sheets beyond such supports are pressed up into raised panels 11 that incline upwardly and outwardly and terminate in vertical flanges 12 at their side edges. The adjacent side flanges of adjacent sheets lie on opposite sides of the upper or channel shaped member of the carline at a sufficient distance therefrom to afford adequate clearance to provide for the distortion of the sub-structure. Above the upper member of the carline and riveted thereto is a transverse seam cap 13 of inverted channel shape with laterally extending flanges 20 at the bottoms thereof that are inclined conformably to the inclination of the inclined marginal portions of the roof sheets, such inclined portions of the sheets and of the seam cap being in contact and the vertical portions of the carline cap being spaced from the vertical flanges of the sheets far enough to afford proper clearance.

The hereinbefore described side plate construction is strong, rigid and compact. Extending the carline and sheet supporting members inwardly from the side plates reduces the space that such carlines and sheets have to span, and such supporting members function as gussets for anchoring the carlines to the side plates. Another important advantage of thus supporting the roof sheets is that it substantially excludes the sunlight which, in some designs of flexible roof, has entered at the ends of the carlines and done more or less damage to the lading. In the present design, the sunlight may be more effectually excluded by chinking with heavy asphaltum or the like, the small spaces 18 at the side edges of the lower member of the carline and between the carline seat and roof sheets. Another advantage is that any water that may leak past the roof sheets will be drained over the side of the car.

In the modification illustrated in Fig. 5, there are no separate supporting members but the Z-shaped side plate has an extra inwardly extending flange 16 at its top and integral with it. The ends of the roof sheets rest on top of this extra flange 16 and the ends of the carlines rest in depressions or seats 17 provided therefor in the top of said extra flange and at proper intervals.

While I have illustrated my invention as applied

to a roof with movably mounted sheets and hollow box carlines, it is obvious that it is also applicable to roofs having non-movable sheets and carlines of various designs.

5. What I claim is:

1. A metal side plate for cars comprising a substantially horizontal web, a depending leg at one end thereof, an upstanding leg at the other end thereof, and a combined carline and roof supporting flange at the top of said last mentioned leg extending therefrom in substantially opposite direction from said web and at an upward inclination approximately equal to the pitch of a car roof, said flange having flat-bottomed depressions therein extending from side to side thereof and constituting seats for carlines, said flange extending straight between depressions and constituting flat seats for roof sheets.

2. An integral metal side plate for cars having carlines with roof sheets movably arranged therebetween, said side plate comprising a substantially horizontal web, a depending leg at one end thereof, an upstanding leg at the other end thereof and a flange at the top of said last mentioned leg extending therefrom in substantially opposite direction from said web and at an upward inclination approximately equal to the pitch of a car roof, said flange having depressions therein constituting seats for said carlines, the portions of the flange located between said depressions being flat and adapted to movably support said roof sheets.

3. A metal side plate for cars comprising a substantially horizontal web, a depending leg at one end thereof, an upstanding leg at the other end thereof and a separate angle member secured to said last mentioned leg with its upper flange extending over the top thereof in substantially opposite direction from said web and at an upward inclination approximately equal to the pitch of a

car roof, said angle member having depressions at intervals in the top thereof constituting seats for carlines, the spaces between said depressions being greater than the width thereof.

4. As an article of manufacture, a member for mounting carlines and roof sheets on the side plates of a car, said member comprising an angle plate with one leg adapted to be secured to a side plate and the other leg forming an oblique angle therewith, said last mentioned leg having flat-bottomed depressions arranged at intervals and shaped to constitute seats for carlines and portions extending straight between said seats and constituting flat supports for the ends of roof sheets.

5. As an article of manufacture, a member for mounting carlines and roof sheets on the side plates of a car, said member comprising an angle plate with one leg adapted to be secured to a side plate and the other leg inclining upwardly at an angle substantially equal to the pitch of a car roof, said last mentioned leg having flat-bottomed depressions arranged at intervals and shaped to constitute seats for carlines, and the portions between said seats being flat and constituting supports for the ends of roof sheets.

6. A metal side plate for cars comprising a substantially horizontal web, a depending leg at one edge of said web, an upstanding leg at the other edge thereof and a continuous combined carline and roof sheet supporting flange at the top of said last mentioned leg, said flange being offset vertically at regular intervals throughout its length to provide widely spaced flat-bottomed carline supporting seats at one elevation alternating with relatively long flat-topped roof sheet supporting seats at a different elevation.

CHARLES DAVID BONSALL.
